[57] CLAIM

The ornamental design for a reading machine for advancing and displaying reading material for physically handicapped persons, as shown.

DESCRIPTION

FIG. 1 is a perspective view of the reading machine for advancing and displaying reading material for physically handicapped persons, showing my new design; FIG. 2 is a side elevational view of my new design; FIG. 3 is an elevational view of one end thereof, looking from the left of FIG. 2; FIG. 4 is an elevational view of the opposite end thereof, looking from the right of FIG. 2; FIG. 5 is a top plan view of the design of FIG. 2; and FIG. 6 is a bottom plan view of the design of FIG. 2.

FIG. 1.

FIG. 2.

FIG. 3.

FIG. 4.

FIG. 5.

FIG. 6.
